DESIGN FOR A BOWL OR SIMILAR ARTICLE

Willis O. Prouty, Hermosa Beach, Calif.

Application September 25, 1939, Serial No. 87,367

Term of patent 14 years

To all whom it may concern:

Be it known that I, Willis O. Prouty, a citizen of the United States and a resident of Hermosa Beach, in the county of Los Angeles and State of California, have invented a new, original, and ornamental Design for a Bowl or Similar Article, of which the following is a specification, reference being had to the accompanying drawing, forming part thereof, in which the single figure is a perspective view of the bowl or similar article, showing my design.

I claim:

The ornamental design for a bowl or similar article, substantially as shown.

WILLIS O. PROUTY.
